UNITED STATES PATENT OFFICE.

CHARLES E. JACKSON, OF ROCKFORD, ILLINOIS.

SWITCH-OPERATING APPARATUS.

SPECIFICATION forming part of Letters Patent No. 699,327, dated May 6, 1902.

Application filed December 18, 1901. Serial No. 86,418. (No model.)

To all whom it may concern:

Be it known that I, CHARLES E. JACKSON, a citizen of the United States, residing at Rockford, in the county of Winnebago and State of Illinois, have invented certain new and useful Improvements in Switch-Operating Apparatus, of which the following is a specification.

This invention relates to a means for operating a railway-switch from a point upon a car or engine approaching the switch and without stopping the car or necessitating the operator to dismount in order to move the switch. As is well known, switches on street-railways are now usually operated from the ground or from the front platform of the car, the car being stopped while the switch is being turned.

The object of this invention is the production of a switch that may be operated from the platform of a moving car without stopping for the switch or materially slackening the speed of the car or that may be operated from the ground if for any reason it is desirable to stop the car to permit the operator to dismount.

In the accompanying drawings, Figure 1 is a plan view of a track fitted with my improved switch-operating apparatus, showing a portion of a car carrying the presser-wheel and its connections. Fig. 2 is a longitudinal section on dotted line 2 2 of Fig. 1. Fig. 3 is a longitudinal vertical section through one of the switch-operating boxes. Fig. 4 is a horizontal section through the box containing the shifting-lever, showing the switch-tongue in elevation. Fig. 5 is a fragmental view of a car, showing the presser-wheel and its actuating mechanism. Fig. 6 is a modified form of this switch-operating device, showing the same adapted to be operated by the pressure of the foot from a point upon the ground by the side of the track.

This switch-operating apparatus is applicable to the ordinary railway-track, of which in the drawings A represents the traction-rails; A', the ties upon which said rails are mounted; A², the switch-tongue, and A³ the platform of a car adapted to travel upon the track. In the middle of the track, at a point adjacent to the switch-tongue A², I set a box B, resting upon and secured to two ties. One side of this box is provided with an integral

collar B' and one end with the integral collars B² and B³. The collar B' receives a pipe B⁴, of any suitable material, extending from the box to a point adjacent to the switch-tongue A². Within the box B, I mount upon the fixed stud B⁵ the pivotal T-shape lever B⁶, the outer end of the stem of which lever is pivotally connected with a rod B⁷, extending to and having pivotal connection with the switch-tongue A². The rod B⁷ is packed with any suitable material within the pipe B⁴ to exclude water from said pipe and from the box B. At the outer ends of the arms forming the transverse portion of the T-shape lever B⁶, I provide openings B⁸ and B⁹ to receive rods, to be hereinafter described, for oscillating the lever B⁶ upon its pivot, and thereby operating the switch-tongue A².

Between the rails of the track and in front of the switch I place the two switch-operating boxes C and D, both having bases C' and D', respectively, extending over and secured in any suitable manner above the upper faces of two ties A', said switch-operating boxes being raised from said ties by the blocks C² and D², respectively, in order to give room for the placing of the switch-operating mechanism above the ties. Within each of the boxes C and D a tilting plate C³ and D³ is mounted at one side of the box upon the pivotal support C⁴ and D⁴, respectively. The pivoted edge of each of these tilting plates is intended to lie flush with that edge of the box upon which it is mounted; but its opposite edge rises upward slightly from the opposite side of the box. An integral arm C⁵ and D⁵ extends downward from the under face of each of the plates C³ and D³, and at its lower end is provided with two openings C⁶ and D⁶. A pipe C⁷ and D⁷ extends from each of the switch-operating boxes C and D to the collars B² and B³, formed on the end of the box B. These pipes are in line with the downwardly-extending arms C⁵ and D⁵, respectively. A rod C⁸, bent at its end to enter one of the openings in the lower end of the integral arm C⁵ of the pivoted plate C³, extends from said arm through the pipe C⁷ into the box B and is there bent to enter the opening B⁸ at one extremity of the transverse portion of the pivotal T-shape lever B⁶. A corresponding rod D⁹ is similarly connected to the lower end of the arm D⁵ in

the switch-operating box D, extends through the pipe D⁷, and enters the opening B⁹ in the opposite end of the transverse portion of the T-shape lever B⁶.

- 5 The box C is provided with a rib C⁹, extending upward from the base C' of said box. This rib is broad enough upon its upper face to receive the device attached to the car before said device strikes the tilting plate C³.
 10 The rib may be sufficiently long to extend to or nearly to the box D. A similar rib D⁹ is formed upon the base D' of the box D and extends rearward some little distance from said box. To exclude water from the pipes C⁷ and D⁷, I cover the openings in the upper ends of the switch-operating boxes C and D with a sheet of rubber C¹⁰ and D¹⁰. This rubber is secured in any suitable manner to the upper edge of each of the boxes, as by the
 15 frame C¹¹ and D¹¹, which frame is intended to be forced downward over said rubber to hold the covering in contact with the sides of the box. This rubber covering is protected by a metallic shoe C¹² and D¹², secured to the top
 20 of each of the plates C³ and D³. The covering is left loose enough to permit the pivotal movement of the plate underneath the covering.
 25

The device attached to the car for operating the switch-tongue comprises a presser-wheel E, rotatably mounted in the bifurcated lower end of a rectangular lever E'. An arm E², extending upward from the rectangular lever E', is attached to a coil-spring E³, which tends to 30 hold the presser-wheel E upward toward the car and from contact with the ground. The lever E' is pivotally mounted upon the stud E⁴, fixed with relation to a portion of the truck of the car. An L-shape lever E⁵ is 35 pivotally mounted between ears E⁶, extending downward from the underside of the platform of the car, and this lever is movable by means of a foot-operated plunger E⁷, pivotally connected with one of the arms of the L-shape lever E⁵, the upper end of which plunger extends through an opening in said platform. The other arm of the L-shape lever E⁵ is connected with the rectangular lever E' by means of the rod E⁸. It will thus be seen that the 40 presser-wheel E may be depressed by the operator when standing upon the front platform of the car by placing his foot upon the upper end of the plunger E⁷.

The operation of my switch-operating apparatus is as follows: As a car approaches the switch from the forward side thereof the operator moves the tongue of the switch into the desired position by depressing the foot-plunger E⁷ and bringing the presser-wheel E 45 into contact with the proper one of the plates C³ and D³. If it is desired to move the switch-tongue in the direction indicated by the arrow, Fig. 1, to cause the car to turn from the main track, the presser-wheel E is brought 50 into contact with the plate C³ of the switch-operating box C. The pressure of the wheel E upon said plate moves the plate C³ down-

ward upon its pivot C⁴, and in moving the plate also moves the arm C⁵, formed integral therewith. This movement of the arm pulls 70 upon the rod C⁸, oscillates the T-shape lever B⁶ upon its pivotal support B⁵, and through the rod B⁷ moves the switch-tongue A².

To move the switch-tongue in the direction contrary to that indicated by the arrow, Fig. 75 1, in order to continue the car upon the main track, the presser-wheel E is brought into contact with the plate D³ of the switch-operating box D. The depression of this plate moves the integral arm D⁵, pulls the connecting-rod D⁸, oscillates the T-shape lever B⁶ upon its pivot B⁵, and pushes the switch-tongue A² toward the right, Fig. 1. The operator upon a car running from the switch-track onto the main track may set the switch 80 to cause the next approaching car to continue upon the main track by moving the presser-wheel into contact with the plate D³, if it is desirable. In other words, the switch may be operated by a car moving either way with relation to the switch-operating boxes C and D. 85

In the modified form shown in Fig. 6 the switch-operating boxes C and D and their connections are dispensed with, also one arm of the T-shape lever B⁶ may be omitted, making said lever a bell-crank lever F. This bell-crank lever F is operated to move the switch-tongue in either direction by means of a link connection F' with a crank-arm F² of an oscillatory shaft F³, which shaft is caused to oscillate by the pressure of the foot of the operator upon either side of a T-shape foot-lever F⁴, secured rigidly to said shaft. The oscillatory shaft F³ is supported in bearings F⁵, secured to one of the ties or to a bed-plate. 90 (Not shown.)

By providing three switch-operating boxes similar to those C and D a three-way switch may be operated. Both tongues of the three-way switch should be pivotally connected with the stem of the T-shape lever B⁶, and the switch-tongues should be susceptible of movement into three different positions by the depression of the tilting plates (similar to those C³ and D³) within the switch-operating boxes. 100 105 110 115

I am aware that many slight changes may be resorted to in the general form and arrangement of the several parts described without departing from the spirit and scope of my invention, wherefore I desire to have it understood that I do not limit myself to the exact details herein shown and described, but claim all such changes and modifications as properly fall within the scope and spirit of my invention. 120 125

I claim as my invention—

1. In a switch-operating apparatus, in combination, a switch-tongue; a pivoted T-shape lever; a rod having a pivotal connection with one arm of said lever and with said switch-tongue; a switch-operating box located between the rails of the track; a switch-operating box aligned with said first-mentioned switch-operating box and located intermedi-

ate said box and said switch-tongue; a plate pivotally mounted near one of its sides in each of said boxes; an arm extending downward from the under side of each of said plates; a rod pivotally connected with the arm of one of said pivoted plates and with one of the arms of said T-shape lever; a rod pivotally connected with the arm of the other of said pivoted plates and with the remaining arm of said T-shape lever; and a device carried by the car for moving one of said plates to actuate said T-shape lever to operate said switch-tongue.

2. In a switch-operating apparatus, in combination, a switch-tongue; a pivoted T-shape lever; a rod having a pivotal connection with one arm of said lever and with said switch-tongue; a switch-operating box located between the rails of the track; a switch-operating box aligned with said first-mentioned switch-operating box and located intermediate said box and said switch-tongue; a plate pivotally mounted near one of its sides in each of said boxes; an arm extending downward from the under side of each of said plates; a rod pivotally connected with the arm of one of said pivoted plates and with one of the arms of said T-shape lever; a rod pivotally connected with the arm of the other of said pivoted plates and with the remaining arm of said T-shape lever; a flexible watertight covering for the upper end of each of said switch-operating boxes; and a device carried by the car for moving one of said plates to actuate said T-shape lever to operate said switch-tongue.

3. In a switch-operating apparatus, in combination, a switch-tongue; a pivoted T-shape lever; a rod having a pivotal connection with one arm of said lever and with said tongue; two aligned switch-operating boxes between the rails of the track, one of said boxes being located intermediate said switch-tongue and the other of said boxes, each of said boxes having bases for securing them to the ties; a tilting plate pivotally mounted near one of its sides within each of said boxes; an arm extending downward from the under side of

each of said plates; a rod forming a connection between the arm of one of said tilting plates and one of the arms of said T-shape lever; a rod forming a pivotal connection between the arm of the other of said tilting plates and the remaining arm of said T-shape lever; a pipe for each of said rods; a pipe for the rod extending between the stem of the T-shape lever and said switch-tongue; a packing in said last-mentioned pipe to prevent the ingress of water to said mechanism; and a device carried by the car for moving said plates to actuate said T-shape lever and to operate said switch-tongue.

4. In a switch-operating apparatus, in combination, a switch-tongue; a pivoted T-shape lever; a rod having a pivotal connection with one arm of said lever and with said tongue; two aligned switch-operating boxes between the rails of the track, one of said boxes being located intermediate said switch-tongue and the other of said boxes, each of said boxes having bases for securing them to the ties; a tilting plate pivotally mounted near one of its sides within each of said boxes; an arm extending downward from the under side of each of said plates; a rod forming a connection between the arm of one of said tilting plates and one of the arms of said T-shape lever; a rod forming a pivotal connection between the arm of the other of said tilting plates and the remaining arm of said T-shape lever; a pipe for each of said rods; a pipe for the rod extending between the stem of the T-shape lever and said switch-tongue; a packing in said last-mentioned pipe to prevent the ingress of water to said mechanism; a presser-wheel carried by the car, for moving said plates to actuate said T-shape lever and to operate said switch-tongue; means for depressing said presser-wheel; and means for returning the presser-wheel to its normal position.

CHARLES E. JACKSON.
